J. F. O'CONNOR.

**SAFETY DEVICE FOR CAR DOOR OPERATING MECHANISMS,
APPLICATION FILED SEPT. 29, 1919.**

1,372,719.

Patented Mar. 29, 1921.

UNITED STATES PATENT OFFICE.

JOHN F. O'CONNOR, OF CHICAGO, ILLINOIS, ASSIGNOR TO WILLIAM H. MINER, OF CHAZY, NEW YORK.

SAFETY DEVICE FOR CAR-DOOR-OPERATING MECHANISMS.

1,372,719.

Specification of Letters Patent. Patented Mar. 29, 1921.

Application filed September 29, 1919. Serial No. 327,192.

To all whom it may concern:

Be it known that I, JOHN F. O'CONNOR, a citizen of the United States, residing at Chicago, in the county of Cook and State 5 of Illinois, have invented a certain new and useful Improvement in Safety Devices for Car-Door-Operating Mechanisms, of which the following is a full, clear, concise, and exact description, reference being had to the 10 accompanying drawings, forming a part of this specification.

This invention relates to improvements in safety devices for car door operating mechanisms.

15 In the operation of freight cars such as hopper, general service and ballast cars, frequent injury to the operators has heretofore occurred due to the sudden loads placed upon the door operating mechanism during 20 the opening operation, the sudden loads causing the shaft to turn rapidly and thereby wrench the claw-bar or other operating tool from the operator's hand and either throwing the operator or causing his injury 25 by being struck with the operating tool.

The object of my invention is to provide a safety arrangement to be used in conjunction with door operating mechanisms for cars of the type indicated which will permit 30 of an unlimited amount of lost motion between the operator's tool and the shaft proper of the door operating mechanism, during the unwinding or unloading operation, after the doors have been started in 35 their opening movement.

More specifically, the object of my invention is to provide a clutch arrangement particularly designed for application to car door operating mechanisms, which clutch arrangement embodies a reversible pawl and ratchet device providing for unlimited lost motion between the claw-bar-actuated element and the operating shaft of the door mechanism proper during the opening 40 movement when the shaft is being rotated under the load on the doors, the pawl and ratchet device being so designed that the door mechanism may be wound to closed and locked position without any lost motion.

45 The invention furthermore consists in the improvement in the parts and devices and in the novel combinations of the parts and devices herein shown, described and made the subject matter of the claims.

50 In the drawing forming a part of this

specification, Figure 1 is an elevational view of a safety device employed in conjunction with the door operating mechanism of a freight car as the same would appear on the side of a car. Fig. 2 is a vertical longitudinal sectional view taken substantially on the line 2—2 of Fig. 1. Fig. 3 is a vertical transverse sectional view taken substantially on the line 3—3 of Fig. 2. And Fig. 4 is a part vertical section, part elevation of a 65 door operating mechanism proper and portions of the car doors with which my invention is adapted to be employed.

In said drawing, 10 denotes the operating shaft of the door operating mechanism 70 proper, said shaft being suitably mounted in bearings provided on the car in any well-known manner. In the drawing I have illustrated one well-known form of door operating mechanism with which my invention 75 is adapted to be used. Said door operating mechanism proper, as shown, includes a cast hub 11 rigidly secured with the shaft 10, said hub having an arm 12 to which is pivoted a link 13. To the opposite end 80 of the link 13 is pivoted a short block or link 14 having a heavy lug 15 which is adapted to seat on the hub 11 against a shoulder 16, when the parts are in closed or locked position. Pivotaly attached to the 85 link 14 is a hook-shaped elongated link 17 pivotally connected at its lower end to one door 18 by the adjustable eye-bolt 19. A second hook-shaped elongated link 20 is also pivotally attached to the link 14 at its upper end and to the other door 21 at its lower end by the eye-bolt 22. The door operating mechanism just described is so designed, that when the doors are in closed position, the operating shaft is relieved of torsional 90 strains and the mechanism is "self-locked." This is due to the location of the various pivotal connections and to open the doors, the shaft 10 is rotated in a clockwise direction as viewed in Fig. 4, through a short arc 100 until the points of pivotal connection become so disposed that the load on the doors, acting through the linkage will tend to rotate the shaft 10 at a high speed. A more detailed description of the door operating 105 mechanism is thought unnecessary for the reason that it is well-known.

The safety device proper, as shown, comprises, broadly, a hub A, a tool-actuated member B, a cover plate C, a ratchet wheel 110

D, a double-ended pawl E, spring F, and pawl operating lever G.

The hub or housing member A is provided with a sleeve 23 having a suitable socket to 5 accommodate the outer end of the shaft 10, the shaft and socket being preferably of non-circular form so as to insure rotation of the hub A and shaft 10 in unison at all times. A rivet 24 is passed through the 10 sleeve 23 and shaft 10 to hold the parts together. Outwardly of the sleeve 23, the hub is provided with a web 25 which extends at right angles to the axis of the shaft 10, the web 25 being provided at its periphery with 15 a circular flange 26 so as to form a housing for the other parts contained therewithin.

The claw-bar or other tool-actuated member B has an outer squared end 27 to receive the claw-bar or other tool and at its inner 20 end is preferably formed integral with the ratchet wheel D. The latter has its inner end rounded as indicated at 28 so as to be journaled in a corresponding bearing 29 provided in the hub member A. Between 25 the squared section 27 and the ratchet wheel D, a circular flange is provided indicated at 30, the latter having a shoulder 31 extending therearound to thereby accommodate the correspondingly flanged and shouldered 30 cover plate C. The latter is mounted within the flange 26 of the hub A and is preferably flush with the outer edge of the flange 26. Said cover plate C is secured to the hub A by any suitable means such as the bolts 35 32-32.

The pawl E has two teeth 33 and 34 at opposite ends thereof, said teeth being so arranged that one co-acts with the ratchet wheel D to effect rotation in one direction 40 and the other tooth in the opposite direction. The pawl E is mounted on a squared section 35 of a short shaft extending through the cover plate C and web 25 and journaled therein. At its inner end, said shaft is 45 threaded as indicated at 36 to accommodate a nut 37 which holds the shaft in place, the nut being prevented from working off by a cotter 38. The pawl E has a notch 39 therein to receive a curled end 40 of the 50 spring F. The latter is carried around the flange 26 of the hub to a point approximately diametrically opposite the pawl where the curled end 41 of the spring is seated in a suitable notch 42 provided in a 55 lug 43 formed integral with the hub. The spring is so designed that it will yieldingly hold the pawl E in either of its two operating positions and will permit either tooth 33 or 34 to ride over the teeth of the ratchet 60 wheel D in accordance with the particular direction in which the ratchet wheel D is rotating relative to the pawl E or the latter rotating relative to the ratchet wheel D.

At its outer end, the pawl-carrying shaft 65 has the short lever G formed integral there-

with, said lever G being adapted for manual operation so as to effect the necessary changes of position of the pawl E, as will be understood.

The hub A is also provided with a series 70 of shoulders 44 around the periphery thereof with which is adapted to co-operate a locking dog 45 suitably pivoted to the car or adjacent bracket 46. A cam (not shown) will ordinarily be employed with the dog 75 45 to positively retain the latter in its locked relation with the hub A, when the doors are in closed position.

The operation is as follows: Assuming the doors in closed position and the parts as 80 shown in the drawing, the operator first releases the dog 45 in the usual manner. The claw-bar is then applied to the squared section 27 of the clutch member B and the clutch member B rotated in a clockwise direction, as viewed in Fig. 1. By reference to Fig. 3, it will be seen that the hub A will be rotated in the same direction without loss of motion due to the relative positions of the ratchet wheel D and tooth 33. This in turn 90 of course will effect rotation of the operating shaft 10 in a similar direction, thereby starting the linkages to unwind. This will continue until such time as the linkages are unlocked and the load is transferred to 95 a torsional strain on the shaft 10. This causes the shaft 10 to continue in a clockwise direction at a high speed and consequently the hub A will also rotate at high speed in a clockwise direction. As this occurs, the 100 tooth 33 of the pawl E will ride freely over the ratchet wheel D so that the latter and consequently the tool in the hands of the operator, will not be carried in unison therewith but on the contrary may be held steady 105 while the opening movement of the doors is being completed. It will be noted from the preceding description, that any desired amount of lost motion between the tool-actuated member of the clutch and the other 110 element of the clutch attached to the shaft, can be obtained and hence the device is of great utility since it can be employed with various types of door operating mechanism, some of which require only a partial revolution and others more than a complete revolution of lost motion in order to obtain the necessary safety for the operator. 115

With the doors in open position, and desiring to close the doors, the operator shifts 120 the position of the pawl E by swinging the short lever G so as to bring the tooth 34 into operative relation with the ratchet wheel D. The operator then applies the claw-bar and winds up the parts by rotating in a counter-clockwise direction until such time as the doors are locked. The locking dog 45 may then be thrown into position as the usual 125 precautionary measure. During the closing movement, it will be noted that no lost mo- 130

tion occurs between the member B and the hub A so that the time and labor are thereby saved. Should the operator leave the pawl E in the position used to close the doors, no 5 injury can result to the operator when the doors are next opened for the reason that, should the operator start to rotate the element B in a clockwise direction, the ratchet wheel D would merely slip by the tooth 34 10 of the pawl E and the operator would therefore be compelled to shift the position of the pawl E in order to start the opening movement of the doors.

The device which I have herein shown 15 and described is comparatively inexpensive to manufacture, is compact, the pawl and ratchet arrangement is completely housed and therefore free from injurious effects of the weather and dirt, and any desired 20 amount of lost motion is obtainable without changes in the mechanism.

Although I have herein shown and described what I now consider the preferred method of carrying out the invention, the 25 same is merely illustrative, and I contemplate all such changes and modifications as come within the scope of the claims appended hereto.

I claim:

30 1. In a safety device for car door operating mechanism having an operating shaft, the combination with two clutch members relatively rotatable an unlimited amount, one of said clutch members being arranged 35 for rigid connection to the shaft and the other adapted to be operated by a claw bar or other similar tool, of a ratchet on one of said clutch members, a reversible pawl on the other of said clutch members, said clutch 40 member adapted for rigid connection to the shaft having a series of peripheral shoulders entirely separate from said ratchet, and a locking dog coöperable with said shoulders.

2. In a safety device for car door operating mechanisms having an operating 45 shaft, the combination with a clutch member adapted to be rigidly secured to the shaft and having a pawl carried thereby and a plurality of peripherally located shoulders; of a clutch member loosely rotatably

mounted with respect to the first named clutch member and adapted to be actuated by a tool, said second clutch member having a ratchet wheel rigid therewith coöperable with said pawl; and a pivoted locking dog 55 adapted to coöperate with said shoulders.

3. In a safety device for door operating mechanism having an operating shaft, the combination with a hollow housing adapted to be rigidly connected with the shaft, said 60 housing comprising a hub and a cover plate, of an element rotatably mounted on said housing and having a ratchet wheel located therewithin, said element having a section adapted to receive an operating tool, and 65 a spring-controlled reversible pawl also mounted within the housing and coöperable with said ratchet wheel.

4. In a door operating mechanism for 70 cars and the like, the combination with a shaft; of a hub rigidly secured to said shaft, said hub having a plurality of peripherally disposed shoulders; a reversible pawl mounted on said hub; a tool operated element rotatably mounted on the hub and 75 provided with a ratchet wheel coöperable with said pawl; means for changing the position of said reversible pawl; and a pivoted locking dog adapted to coöperate with 80 said shoulders.

5. In a safety device for car door operating mechanism having an operating shaft, the combination with a hollow housing adapted to be rigidly connected with said 85 shaft, said housing having on the interior thereof a clutch-acting element; of a member rotatably mounted with respect to said housing and having a coöperating clutch element within the housing, said last named member being adapted to be operated by a 90 claw bar or the like, one of said clutch elements consisting of a ratchet and the other a reversible pawl; and means, operable from the outside of the housing, for shifting the 95 position of the pawl.

In witness that I claim the foregoing I have hereunto subscribed my name this 18th day of Sept., 1919.

JOHN F. O'CONNOR.
